CIRCUIT BREAKER

John G. Jackson, Detroit, Mich., assignor to
 Square D Company, Detroit, Mich., a corpora-
 tion of Michigan

Application September 19, 1941, Serial No. 411,519

17 Claims. (Cl. 200—116)

This invention relates to devices for making and breaking electrical circuits and has for its object the provision of an improved operating means for an automatic electric circuit breaker.

Another object of the present invention is to provide in an automatic electric circuit breaker an improved form of latching means for the releasable contact carrier.

Another object of the present invention is to provide in an automatic circuit breaker an improved latch and current responsive operating means therefor.

Another object of the present invention is to provide a multi-pole circuit breaker having improved operating means therefor.

Another object of the present invention is to provide a multi-pole circuit breaker having releasable contact carriers and current responsive latches therefor with means for releasing all the carriers upon an overload through one.

Other objects and features of the invention will be readily apparent to those skilled in the art from the following specification and appended drawings:

Figure 1 is a front elevational view of the circuit breaker according to the present invention with the front cover partially broken away to show internal parts.

Figure 2 is a vertical sectional view taken on the line II—II of Figure 1.

Figure 3 is a vertical sectional view taken on the line III—III of Figure 1.

Figure 4 is a view similar to Figure 3, but with the contacts shown in separated position.

Figure 5 is a view similar to Figure 2, but with the operating parts shown in manual off and/or reset position.

Figure 6 is a view similar to Figure 2, but with the parts in overload tripped position.

The circuit breaker as illustrated in the drawings comprises an outer enclosing box 1 having a cover 2 mounted thereon. Within the box and upon the back wall 3 thereof is mounted a generally cup shaped insulating base 4 having a pair of dividing walls 5 and 6 to provide three compartments therein. A metallic cover 7 is preferably sealably attached to the base 4 by means of spunover portions of rivets or in any other manner and an insulating sheet 8 of fibre or other material is disposed in back of the metallic cover 7.

Within the central compartment 9 there is provided a latch 11 for a purpose to be herein-after described, slideably supported upon a generally L shaped member 12 which is guided for

rectilinear movement at right angles to the back of the base by formations within the base. A spring 13 is carried by the latch 11 upon a portion thereof and interposed between a leg 14 of the movable member 12 and shoulder surfaces 15 on the latch and continually biases the latch for movement toward the lower end of the base 4 and away from leg 14. A cotter pin 16 carried by the latch 11 determines its normal extended position. A second spring 17 interposed between the back wall 18 of the base and an extension 19 of the movable member 12 continually biases the member for movement forwardly toward the front of the base.

Upon a shaft 21 received within notches in the dividing walls 5 and 6 is mounted a rotary handle 22 having an interior camming surface adapted to cooperate with the flat front surface of the rectilinearly movable member 12 and including a stable contacts engaged flat surface 23.

The latch 11 is biased by spring 13 to releasably engage a surface 20 of a movable member 24 which is guided for rectilinear movement at right angles to the back of the base by slots formed within the opposing dividing walls 5 and 6. The member 24 is adapted to extend through these slots and into the compartments 25 and 26 provided at either side of the central compartment 9. Fibre plates 27 and 28 are disposed at either end of the central compartment 9 to sealably enclose it against access.

Within the compartments 25 and 26 are disposed similar individual circuit breaker mechanisms embodying a floating contact bar or switch member 29 having a notch 31 in its front edge receiving the front edge of a cooperating slot provided in the longer leg of a generally U shaped member 32. A spring 33 engages the under side of the contact bar 29 and exerts its force therethrough to maintain the member 32 forwardly and to bias the contact bar 29 for clockwise movement about its pivotal engagement with member 32. A stud 30 is provided upon the bight portion of the U shaped member 32 engageable with the front of the base to limit forward movement of the member. The contact bar 29 is provided at its upper end with a contact surface 34 and at the opposite end is notched as at 35 to receive the end of a metallic piece 36 rigidly secured to the rectilinearly movable member 24 and movable therewith.

Upon an end ledge 37 at the top of the circuit breaker is mounted a connector 38 as by means of a spun over portion of a metallic insert 38. A terminal stud 41 is provided threaded into

the metallic insert 39. The connector 38 extends into the interior of the breaker and there carries a stationary contact 42. The top portion of the base is sealed off by means of an insulating wall 43 of fibre or other material preventing access to the interior; and the arc chamber surrounding the contact 42 is provided with further lining walls formed by side wall 44 and bottom wall 45, preferably of fibre, and with a barrier wall 46 also of fibre and serving to separate the arc chamber from the circuit breaker mechanism and which is provided with a slot 47 closely receiving the contact bar 29 which extends through the slot into the arc chamber whereby the movable contact surface 34 may cooperate with the stationary contact 42.

At the bottom end of the circuit breaker and upon a ledge 48 is mounted a connector 49 as by means of a spun over portion of a metallic insert 51 having a terminal stud 52 threaded therein. The connector 49 extends within the interior of the breaker and has its central interior end pressed out as at 53 and to this end is rigidly secured as by welding a current responsive bi-metallic strip 54. A stud 55 carried by the connector 49 presses against the pressed out portion 53 and serves to adjust the position of the bi-metallic and hence the current rating to which the breaker is responsive. A flexible lead 56 connects the free end of the bi-metallic member 54 to the contact bar 29. Rigidly secured to the latch 11 as by welding are two oppositely directed L shaped members 57 adapted to extend through slots 58 provided in the walls 5 and 6 and into compartments 25 and 26. The members 57 are provided with flanges 59 extending toward the back of the base 4 and carrying insulating buttons 61 adapted to be engaged by the bi-metallic members 54 whereby movement of either of the bi-metallic members 54 when heated will effect movement of the latch 11 into unlatching position. Insulating walls 62 serve to seal off the bottom of the breaker from the exterior.

The operation of the circuit breaker will now be described. As specifically shown herein, the circuit breaker is of the multi-pole form and the individual circuit breaker mechanisms will perform simultaneously. As illustrated in Figures 2 and 3, the circuit breaker is in the closed circuit position. To place the parts in manual "off" position, the handle 22 is rotated in clockwise direction until the surface 23 is disengaged from the front surface of the movable carrier member 12 whereby the force exerted by spring 17 will force both the member 12 and the latch 11 supported thereon rectilinearly forward toward the front of the base. This movement of the latch 11 away from the rectilinearly movable member 24 releases the restraining force thereon so that the force exerted by the compression springs 33 is free to effect clockwise rotation of the contact bars 29 to simultaneously separate the contact surfaces 34 from the contact surfaces 42. Through its engagement with the contact bars 29 the movable member 24 will be moved rectilinearly forward toward the front of the base by the springs 33 until the upper portion of the member 24 is engaged by the insulating liner 8 whereby all further movement of the circuit breaker parts will be halted. Thus it is seen that the removal of the restraint of handle 22 upon the latch 11 provides for simultaneous movement of both contact bars 29 to simultaneously break both poles of the breaker. To again place the parts in closed circuit position the handle is

rotated in a counterclockwise direction whereby latch 11 will be moved to positively move member 24 and contact bars 29 into contacts engaged position.

Upon the occurrence of an overload through either of the bi-metals 54 it will become heated and bend counterclockwise as viewed in Figure 3. In this movement it pushes upon the insulating button 61 to rectilinearly move latch 11 against the bias of spring 13 to disengage the latch from the rectilinearly movable member 24. When the member 24 is released the contact bars 29 are then free to simultaneously rotate about their pivotal engagement with the member 32 and under the bias of compression spring 33 and to rectilinearly move the member 24 into the position shown in Figure 6.

To reset the breaker the operating handle 22 is rotated clockwise to "off" position whereby spring 17 will effect a rectilinear movement of the supporting member 12 to carry the latch 11 in a like direction to a position where the compression spring 13 can act to effect rectilinear movement of the latch in a direction substantially at right angles to the direction of movement effected by spring 17 and into re-engagement with the rectilinearly movable member 24.

It is to be noted that the rectilinearly movable member 24 is made sufficiently long so that when the front edge thereof engages the front of the base, the latch engaging surface 20 thereon will be stopped in a position to which the latch 11 may be readily moved by springs 13 to effect re-engagement therewith after an overload release has occurred.

While certain preferred embodiments of the invention have been specifically disclosed, it is understood that the invention is not limited thereto as many variations will be readily apparent to those skilled in the art and the invention is to be given its broadest possible interpretation within the terms of the following claims.

What is claimed is:

1. In an automatic electric circuit breaker, a stationary contact, a movable member having a contact surface adjacent to one end adapted to cooperate with said contact, an actuating member, means biasing the opposite end of said movable member into engagement with said actuating member, a relatively fixed pivot for said movable member interjacent said biasing means and contact surface, manual means operative upon said actuating member to move said movable member against said biasing means to contacts engaged position and current responsive means mounted independently of said movable member to effect automatic movement of said movable member to contacts separated position.

2. In an automatic electric circuit breaker, a stationary contact, a movable contact bar carrying a contact surface adjacent one end adapted to cooperate with said contact, means biasing said movable contact toward disengaged position, a movable element engaging the opposite end of the bar, manual means operative on said movable element to move said bar against said biasing means to contacts engaged position, and current responsively controlled latching means independently mounted of said contact bar, and releasably engageable with said movable element, said bar being movable to contacts disengaged position upon release of said movable element by said latching means on the occurrence of an overload.

3. In an automatic electric circuit breaker, a

stationary contact, an elongated member carrying a contact surface adjacent to one end adapted to cooperate with said contact, a relatively fixed pivot for said elongated member, a rectilinearly movable member engaging the opposite end of the elongated member, and operative to move said elongated member about said pivot to contacts engaged position, a latch engaging said rectilinearly movable member, a current responsive element operative on said latch to effect release of said rectilinearly movable member, and biasing means interjacent the ends of the elongated member adapted to move said elongated member to contacts disengaged position upon release of said rectilinearly movable member.

4. In an automatic electric circuit breaker, a stationary contact, a movable switch member having a contact surface at one end thereof, a relatively fixed pivot for said switch member, force applying means engaging the opposite end of the switch member for moving said switch member to contacts engaged position, biasing means for said switch member interjacent the fixed pivot and said opposite end of the switch member for effecting a substantial pressure between said contacts, and current responsive means mounted independently of said switch member and operable on said force applying means to effect movement of said switch member to contacts separated position.

5. In an automatic electric circuit breaker, a stationary contact, a movable switch member having a contact surface at one end thereof, a relatively fixed pivot therefor, means intermediate the ends of the switch member biasing it toward contacts disengaged position, actuating means engaging the opposite end of the switch member for moving said switch member against said biasing means to effect engagement of the contacts whereby said biasing means becomes operative upon said switch member to provide a substantial pressure between said contacts, and current responsive means mounted independently of said switch member and cooperating with said actuating means to effect movement of said switch member by said biasing means to contacts disengaged position.

6. In an automatic electric circuit breaker, a stationary contact, a switch member movable to move said movable contact into and out of engagement with said stationary contact, a rectilinearly movable member operatively engaging said switch member, a movable latch engageable with said rectilinearly movable member, means for moving said latch rectilinearly to positively move said rectilinearly movable member and said switch member to contacts engaged position, and current responsive means for moving said latch rectilinearly but in a direction at right angles to said first path of movement to release said rectilinearly movable member to effect movement of said switch member to contacts disengaged position.

7. In an automatic electric circuit breaker, a stationary contact, a movable contact, a switch member movable to move said movable contact to engaged and disengaged positions, biasing means for said switch member, a rectilinearly movable member operatively engaging said switch member, a movable latch engageable with said rectilinearly movable member, spring means continually biasing said latch toward engaged position, means for moving said latch rectilinearly to positively move said rectilinearly movable member and said switch member to contacts

engaged position, and current responsive means for moving said latch rectilinearly and against the bias of said spring means but in a direction at right angles to said first path of movement to release said rectilinearly movable member, said switch member moving to contacts disengaged position under the force of said biasing means upon release of said rectilinearly movable member.

10. 8. In an automatic electric circuit breaker, stationary and movable contacts, a switch member movable to move said movable contact for cooperation with said stationary contact, a movable member operatively connected to said switch member for movement thereof, manual means for moving said movable member rectilinearly to actuate said switch member to contacts engaged position, and current responsive means separate from said manual means for moving said movable member rectilinearly and in a direction substantially at right angles to its first path of movement to effect movement of said switch member to contacts disengaged position.

9. In an automatic electric circuit breaker, a stationary contact, a movable contact, a contact member movable to move said movable contact to engaged and disengaged positions, a first rectilinearly movable member having operative engagement with said contact member, a movable

30 supporting element, a second rectilinearly movable member slideably carried by said supporting element and having engagement with said first rectilinearly movable member, manual means operative to move said supporting element to move said second rectilinearly movable member to effect positive movement of said first rectilinearly movable member and of said contact member to contacts engaged position, and current responsive means for moving said second rectilinearly movable member to release said first rectilinearly movable member, said contact member moving to contacts disengaged position irrespective of any movement of said supporting element upon release of said first rectilinearly movable member.

10. In an automatic electric circuit breaker, a stationary contact, a movable contact, a contact member movable to move said movable contact for engagement and disengagement with said stationary contact, spring means continually biasing

50 said contact member toward disengaged position, a movable support member, a rectilinearly movable member having operative engagement with said contact member, a movable latch slideably carried by said movable support, and having engagement with said rectilinearly movable member, a second spring means continually biasing said latch toward engaged position, manual means operative to actuate said support member

60 to move said latch to effect positive movement of said rectilinearly movable member and of said contact member to contacts engaged position, and current responsive means for moving said latch rectilinearly and in a direction other than the first direction of movement to release said rectilinearly movable member to effect movement of said contact member to contacts disengaged position under the bias of said first spring means and independently of any movement of said support member.

65 11. In an automatic electric circuit breaker, a stationary contact, a movable contact, a contact member movable to move said movable contact for cooperation with said stationary contact to make and break an electric circuit therethrough,

a rectilinearly movable member having operative engagement with said contact member, spring means continually biasing said contact member toward disengaged position, a movable support member, a rectilinearly movable latch slideably carried by said movable support and having engagement with said rectilinearly movable member, a second spring means continually biasing said rectilinearly movable latch toward engaged position, manual means operative to ON position for actuating said movable carrier member to rectilinearly move said latch to effect positive movement of said rectilinearly movable member and of said contact member to contacts engaged position, a third spring means operative upon said support member for movement thereof toward contacts disengaged position upon movement of said manual means to OFF position, and current responsive means for moving said latch rectilinearly and in a direction substantially at right angles to its first path of movement and against the bias of said second spring means to release said rectilinearly movable member for effecting movement of said contact member from contacts engaged to contacts disengaged position under the bias of said first spring means and independently of any movement of said support member.

12. In an automatic electric circuit breaker, a stationary contact, a movable contact, a switch member movable to move said movable contact for cooperation with said stationary contact to make and break an electric circuit therethrough, a rectilinearly movable member having an operative engagement with said switch member, biasing means for said switch member and said rectilinearly movable member, a movable latch having engagement with said rectilinearly movable member, manual means operable to ON position to move said latch rectilinearly to positively move said rectilinearly movable member to actuate said switch member to contacts engaged position, and current responsive means for moving said latch rectilinearly to release said rectilinearly movable member, said rectilinearly movable member and said switch member moving under the force of said biasing means to contacts disengaged position when said rectilinearly movable member is released, and spring means adapted to move said latch into reengagement with said rectilinearly movable member upon movement of said manual means to OFF position.

13. In an automatic electric circuit breaker, a stationary contact, a movable contact, a switch member movable to move said movable contact into and out of engagement with said stationary contact, a rectilinearly movable supporting member, a latch slideably carried thereby, a rectilinearly movable member having operative engagement with said switch member and being engaged by said latch, a manual operator operable to ON position to move said carrier and said latch rectilinearly for positively actuating said rectilinearly movable member and said switch member to contacts engaged position, and current responsive means for moving said latch rectilinearly to release said rectilinearly movable member, said switch member moving to contacts disengaged position upon release of said rectilinearly movable member, spring means operable

to move said carrier and said latch rectilinearly and in a reverse direction to said first direction of movement upon movement of said manual operator to OFF position and a second spring means operable to move said latch rectilinearly and at right angles to said path of reverse movement into reengagement with said rectilinearly movable member.

14. In an automatic electric circuit breaker, a stationary contact, a movable switch member having a contact surface adjacent to one end adapted to cooperate with said stationary contact, a slideably mounted force applying means engageable with the opposite end of said switch member for effecting positive movement thereof to contacts engaged position, biasing means intermediate the ends of said switch member, manual means for moving said force applying means, a relatively fixed pivot for said switch member, and a member automatically operable on current overloads and normally engaging said force applying means and releasable therefrom on current overloads to effect movement of said switch member about said pivot.
15. In an automatic electric circuit breaker, a stationary contact, a movable switch member having a contact surface adjacent to one end adapted to cooperate with said contacts, actuating means engaging the opposite end thereof for effecting positive movement of the switch member to contacts engaged position, a relatively fixed pivot for said member, biasing means for said member intermediate the pivot and said opposite end, and means for effecting manual movement of said movable switch member against said biasing means to contacts engaged position, said means including a member mounted independently of said switch member and normally engaging said actuating means and being automatically movable on the occurrence of current overload to release said actuating means.

16. In an automatic electric circuit breaker, a stationary contact, a contact bar carrying a contact surface at one end adapted to cooperate with said stationary contact, an actuating member for effecting movement of said contact bar to ON position, means intermediate the ends of the bar biasing the opposite end thereof into engagement with said actuating member, a rectilinearly movable latching member normally engaging said actuating member during manual operation, and being automatically movable out of engagement therewith on the occurrence of a current overload, and fixed means engaging said bar, said bar being freely rotatable relative to said fixed means upon release of said actuating member from said latching member.

17. In an automatic electric circuit breaker, a stationary contact, a switch member having a contact surface adjacent to one end adapted to cooperate with said stationary contact, a movable member operatively engaging the opposite end of said switch member for effecting movement thereof to the ON position, a relatively fixed pivot for said switch member, a rectilinearly movable latch automatically operable in response to current overload normally releasably engaging said movable member, and manually operable means effecting positive movement of said latch to actuate said movable member to positively move said switch member to contacts engaged position.

JOHN G. JACKSON.
